[57] CLAIM

The ornamental design for a end clip for a heat exchanger tube cleaning shuttle brush retaining basket, substantially as shown and described.

DESCRIPTION

FIG. 1 is a side elevation of an end clip for a heat exchanger tube cleaning shuttle brush retaining basket, showing my new design;

FIG. 2 is a front elevation view thereof; and

FIG. 3 is a rear elevation view thereof.

The retaining basket shown in phantom in FIG. 1 is for illustrative purposes only and forms no part of the design.
